UNITED STATES PATENT OFFICE.

JOHN C. MOSS, OF ROSSTON, TEXAS.

HAY-KNIFE.

SPECIFICATION forming part of Letters Patent No. 278,584, dated May 29, 1883.

Application filed March 10, 1883. (No model.)

To all whom it may concern:

Be it known that I, J. C. Moss, a citizen of the United States, residing at Rosston, in the county of Cooke and State of Texas, have invented certain new and useful Improvements 5 in Hay-Knives; and I do declare the following to be a full, clear, and exact description of the invention, such as will enable others skilled in the art to which it appertains to make and 10 use the same, reference being had to the accompanying drawings, and to letters or figures of reference marked thereon, which form a part of this specification.

Figure 1 of the drawings is a perspective 15 view of my hay-knife; and Fig. 2 is a plan view, part sectional, of the same.

This invention has relation to hay-knives 20 designed to cut hay from the rick; and it consists in the construction and novel arrangement of the forked frame, the lever pivoted thereto, slotted at one end and carrying at the other end a cutting-blade working through 25 bearings in the fork, the crank pivoted to the frame and engaging the slot of the lever, and the pressure-head or cross-bar connected to the outer end of the frame, all as hereinafter set forth.

In the accompanying drawings, the letter 30 A designates the main frame, consisting, preferably, of two bars, B B, bent at one end to form the fork C of the frame, and at the other to provide a slot or opening, D.

To the outer end of the frame A is attached 35 the pressure-head or bar E, which is usually pivoted to permit the frame to be turned while the bar E is pressed against the body of the operator.

F indicates the lever, one end of which extends into the opening D, and is slotted, as indicated at G. This lever is pivoted to the bars of the main frame near their point of divergence, as indicated at H, and carries at its end the knife K, which is pivoted to said lever at its middle portion, its ends extending

through slots l l of the fork-arms L L, as 45 shown in the drawings. The cutting-edge of the knife K is usually serrated, as indicated at m. In the slotted bearings l are provided anti-friction rollers r, which engage the rear 50 edge of the knife, and are designed to facilitate its vibration.

P indicates the crank whereby the lever is vibrated, operating the knife. This crank is preferably made with two handles, Z Z, so that it can be worked with both hands. The 55 bearing end v of the crank is provided with an anti-friction roller, s, which works in the slot G of the lever.

The fork of the frame is provided with pointed projections V, which extend beyond 60 the cutting-edge of the knife and serve to hold the instrument firmly in position when pressed into the rick. A transverse guide-bar, I, supports the lever near the middle of the knife.

Having described this invention, what I 65 claim, and desire to secure by Letters Patent, is—

1. A hay-knife having a forked frame and lever pivoted thereto, an operating-crank engaging a slot of the lever, and a vibratory reciprocating knife working through bearings 70 in the fork-arms and pivoted to the end of the lever, substantially as specified.

2. The hay-knife consisting of bent bars forming a fork-frame, a lever pivoted thereto 75 and carrying a transversely-reciprocating knife working in bearings of the fork-frame, the crank pivoted to the frame and engaging a slot of the lever, and the pressure-head or cross-bar pivoted to the outer end of the frame, 80 substantially as specified.

In testimony whereof I affix my signature in presence of two witnesses.

JOHN C. MOSS.
